Howard C. Thompson
ATTORNEY

UNITED STATES PATENT OFFICE

CHARLES P. RICE, OF NEW YORK, N. Y.

DISPLAY STAND

Application filed July 28, 1926. Serial No. 125,359.

This invention relates to display stands and particularly to devices of this class adapted for use in displaying, in the most advantageous manner, merchandise of any kind or class; and the object of the invention is to provide a stand comprising a plurality of adjustably and detachably connected parts so constructed as to permit the quick assemblage of the parts in the construction 10 of a stand of predetermined dimensions; a further object being to provide a stand composed of a plurality of shelf members and spaced standards composed of telescoping and detachably coupled parts in connection 15 with which the respective shelf members are mounted whereby a display stand may be produced to display numerous articles of merchandise on a comparatively small floor space, it being understood that the shelves 20 are arranged one above the other and may be of like or different dimensions; a further object being to provide a display stand employing adjustable shelf members which may be arranged in a horizontal position or collectively in an inclined position or one half 25 of each shelf member arranged in different positions with relation to each other, means being provided for the adjustment of the shelf members or the separate parts thereof 30 and for retaining the same in predetermined positions of adjustment; and with these and other objects in view, the invention consists in a display stand of the class and for the purpose specified, which is simple in construction, efficient in use, and which is constructed 35 as hereinafter described and claimed.

The invention is fully disclosed in the following specification, of which the accompanying drawing forms a part, in which the 40 separate parts of my improvement are designated by suitable reference characters in each of the views, and in which:

Fig. 1 is a side and sectional view of a display stand or part of a display stand made 45 according to my invention.

Fig. 2 is a plan view of one end portion of the stand shown in Fig. 1.

Fig. 3 is a sectional detail view showing 50 the manner of supporting a standard in connection with the base of the display stand,

the section being on the line 3—3 of Fig. 1.

Fig. 4 is an end view of one of the shelf members employed with part of the construction broken away and in section.

Fig. 5 is a partial section on the line 5—5 of Fig. 2.

Fig. 6 is a partial section on the line 6—6 of Fig. 4.

Fig. 7 is a partial section on the line 7—7 of Fig. 1 and showing a part of one shelf member in an inclined position.

Fig. 8 is a sectional detail view on the line 8—8 of Fig. 7; and,

Fig. 9 is a perspective detail view of one of a number of standards which I employ.

In carrying my invention into effect, I provide a base 10 comprising an elongated beam 10^a having crossheads 11 at its ends. The crossheads 11 form leg members for the stand and have at their outer ends, ball castors 12 to permit of the movement of the frame over a floor surface. The beam 10^a in the construction shown is composed of two parts, between which is mounted at spaced intervals, two upwardly directed square socket members 13 which project above the upper face of the beam 10^a and serve to support standards 14 in connection with the base. The standards 14 consist of square tubings provided within one end thereof with smaller tubings, welded or otherwise secured in position, and the ends 15 of which project to form coupling members insertible into the socket members 13 and also into the ends of adjacent standards, it being understood that one standard is placed upon the other in the construction of the display stand, especially in employing more than one shelf member.

I also employ shelf members 16, two of which are shown in Fig. 1 of the drawing for illustrative purposes, it being understood that any number of said shelf members may be employed and while they are of the same general construction, they may be of different outside dimensions. However, and if desired, they may be of the same dimensions. In Fig. 1 of the drawing, the upper shelf member is of slightly less outside dimensions than the lower shelf member.

Aside from the outer dimensions of the 100

separate shelf members, the structure thereof is the same and the description of one shelf member will apply to the other. Each shelf member 16 is composed of separate parts 16^a and 16^b each part constituting a shelf part which may cooperate with the other part to form a flat shelf or an inclined shelf, or which may be independently adjustable with relation to the other part to form thereof independent shelf parts. Each part 16^a—16^b of the shelf member 16 is provided with a board or slab 17 which may be composed of metal, wood or a composition of any kind or class, and these slabs carry on their bottom faces bracket portions 18 arranged in alinement with the standards 14 employed and at one side of recesses 19 on the adjacent edges of the slabs and through which the standards 14 pass as seen in Fig. 2 of the drawing. The brackets 18 are riveted or otherwise secured to the slab 17, said brackets being L-shaped in form in cross section, and the projecting flange is provided with spaced apertures 20, by means of which one end of brace levers 21 may be adjustably coupled with relation to the separate parts 16^a—16^b of the shelf member. The inner or adjacent ends of the brackets 18 have bearing portions 22 which overlap one another and are pivoted together and to a shelf supporting block 23 adjustably mounted in connection with the standards 14.

The block 23 comprises an oblong body part 24 in the form of a short tube, and the standards 14 are adapted to fit snugly in one end of said body 24, a U-shaped shoe piece 25 fitting in the other end of said body and adapted to be forced into engagement with the standard 14 by means of a clamp screw 26, the pointed end 27 of which is adapted to engage the outer surface of the standard 14. The screw 26 has a large head 28 by means of which the same may be operated by hand. Welded or otherwise secured to the inner face of that part of the body 24 through which the standard 14 passes is an attaching or mounting strip 29, the upper end of which carries the pivot pin 30 in the form of a loose rivet which passes through the bearings 22 on the ends of the brackets 18, forming the pivoted connection of said brackets, and in this way, the parts 16^a and 16^b of the shelf member are mounted in connection with the supporting block 23. A bolt 31 is mounted in the lower end of the strip 29, and is provided with a winged nut 32 for engagement with the outer ends of the levers 21 to support said levers in different positions of adjustment in connection with the block 23, the last named end of said levers 21 having spaced apertures 33 through which the bolt 31 is adapted to pass.

It will be understood that the pivotal connection of the separate parts 16^a and 16^b of the shelf member as above described, forms a

hinge construction. In addition to this hinge construction, I also provide at the ends of the shelf member, hinges 34 for pivoting the parts 16^a and 16^b together independent of the supporting blocks 23 employed in connection with each shelf member. The hinges 34 are supported in connection with a peripheral flange or rim portion 35 on the shelf member or the separate parts thereof, said flange extending above and below the slabs 17. In the construction shown, and as seen in Fig. 7 of the drawing, said flanges are composed of wood or other strips 35^a enclosed with a sheet metal casing 35^b. The inner faces of the strips are grooved as seen at 36 to receive the outer edges of the slabs 17. The flanges or rim portions 35 are secured to the slabs 17 in any desired manner and form means for supporting articles placed on the shelf member or the separate parts thereof against displacement, especially when the shelf member or other of its parts are arranged in an inclined position as seen at the right of Fig. 7 of the drawing.

It will be seen from the foregoing that each shelf member when assembled, includes the two parts 16^a and 16^b with the brackets 18 thereon arranged in spaced relation and with two supporting blocks 23 on each shelf member adjacent the brackets and in alinement with the recesses 19 to receive the standards 14 which are detachably coupled with the base 10 of the device, two or more of the standards being placed one upon the other and interlocked by the couplings 15, the lower portion of the standards entering the sockets 13 as clearly seen in Fig. 1 of the drawing. In assembling the complete device, the standards are first mounted upon the base, and the lowermost shelf member to be employed in a predetermined display stand is passed downwardly over the standards with the screw 26 in an outward position. When the shelf member has been adjusted to the desired height, the screw 26 is operated to fixedly retain the blocks 23 of such shelf member in position, after which, another shelf member which may be of the same or less dimensions is passed downwardly over the standards and secured in position in the manner of securing the first named shelf member. Any number of shelf members may be placed one upon the other and secured to the standards and adjusted to required or desired spaced relation as will be apparent.

It will also be understood that the separate parts 16^a—16^b of each shelf member may be retained in horizontal position as seen in Figs. 1 and 2 of the drawing, or either of said parts may be raised or lowered by the adjustment of the brace levers 21. In Fig. 7 of the drawing, the part 16^b of one shelf member is shown in a lowered and inclined position, the same to be swung on the pivot pin 30 and the hinges 34. It will also be apparent that both

parts of each shelf member may be raised or lowered as may be desired, especially when the display stand is used in the center of a room or compartment, but in placing the stand against a wall, the straight or horizontal part may be placed against the wall and the inclined part arranged outermost. Further, it will be apparent that the uppermost shelf member employed may be raised to the upper ends of the standards or the uppermost standard employed to form a flat table member, and the member or members beneath such flat table member may constitute shelves for supporting or storing boxes or cases or the articles thus displayed for sale or other purposes, on the table member.

It will be apparent from the foregoing, that my display stand by virtue of its construction and principally the interchangeability of the parts and the adjustment thereof, will facilitate the attractive display of articles of various kinds and classes in establishments of any kind, and also serve with utility, as a bench or table member.

While I have shown certain details of construction for carrying my invention into effect, it will be apparent that I am not necessarily limited to the structural details herein shown and described, and various changes therein and modifications thereof may be made within the scope of the appended claims without departing from the spirit of my invention or sacrificing its advantages.

Another distinctive feature of my invention resides in the fact that the several parts of my improved stand when knocked down or detached one from the other facilitates the compact wrapping or crating of all of the parts of a particular display stand unit in a comparatively small package.

Having fully described my invention, what I claim as new and desire to secure by Letters Patent, is:—

1. A display stand of the class described comprising spaced rodlike standards, a shelf member adapted to be detachably and adjustably mounted on said standards and comprising a unit structure consisting of side shelf parts, tubular couplings arranged intermediate said parts and inwardly of the end portions thereof and through which said standards are adapted to pass, said couplings including common pivots for the shelf parts whereby said shelf parts may be independently adjustable at either and both sides of the stand, and said couplings including brace arms on said shelf parts and adjustably mounted in connection with said couplings to support the shelf parts in different positions of adjustment.

2. A display stand of the class described comprising spaced rod-like standards, a shelf member adapted to be detachably and adjustably mounted on said standards and comprising a unit structure consisting of said

shelf parts, tubular couplings arranged intermediate said parts and inwardly of the end portions thereof and through which said standards are adapted to pass, said couplings including common pivots for the shelf parts whereby said shelf parts may be independently adjustable at either and both sides of the stand, said couplings including brace arms on said shelf parts and adjustably mounted in connection with said couplings to support the shelf parts in different positions of adjustment, and said arms being adjustably supported in connection with said shelf parts.

3. A display stand of the class described comprising spaced rod-like standards, a shelf member adapted to be detachably and adjustably mounted on said standards and comprising a unit structure consisting of side shelf parts, tubular couplings arranged intermediate said parts and inwardly of the end portions thereof and through which said standards are adapted to pass, said couplings including common pivots for the shelf parts whereby said shelf parts may be independently adjustable at either and both sides of the stand, said couplings including brace arms on said shelf parts and adjustably mounted in connection with said couplings to support the shelf parts in different positions of adjustment, and means on said couplings for securing the same in different positions of adjustment on said standards.

4. A display stand comprising a base member, a standard on said base member, a shelf member detachably and adjustably supported in connection with said standard, means for retaining said shelf member in predetermined positions of adjustment on said standard, and said shelf member being composed of separate shelf parts having a common pivot on said means and arranged centrally with reference to said standard and extending at opposite sides of said standard and adjustable relatively to each other on said pivot.

5. A display stand comprising a base member, a standard on said base member, a shelf member detachably and adjustably supported in connection with said standard, means for retaining said shelf member in predetermined positions of adjustment on said standard, said shelf member being composed of separate shelf parts having a common pivot on said means and arranged centrally with reference to said standard and extending at opposite sides of said standard and adjustable relatively to each other on said pivot, and means involving brace levers adjustably coupled with said first named means for supporting said shelf parts in different positions of adjustment.

6. A display stand comprising a base member, a standard on said base member, a shelf member detachably and adjustably supported in connection with said standard,

- means for retaining said shelf member in predetermined positions of adjustment on said standard, said shelf member being composed of separate shelf parts having a common pivot on said means and arranged centrally with reference to said standard and extending at opposite sides of said standard and adjustable relatively to each other on said pivot, means involving brace levers adjustably coupled with said first named means for supporting said shelf parts in different positions of adjustment, said parts of the shelf member having peripheral flanges, and said standard being composed of separate detachably coupled parts.
7. A display stand comprising a base member, a standard on said base member, a shelf member detachably and adjustably supported in connection with said standard, means for retaining said shelf member in predetermined positions of adjustment on said standard, said shelf member being composed of separate shelf parts having a common pivot on said means and arranged centrally with reference to said standard and extending at opposite sides of said standard and adjustable relatively to each other on said pivot, means involving brace levers adjustably coupled with said first named means for supporting said shelf parts in different positions of adjustment, and said brace levers being adjustably coupled with said shelf parts.
8. A display stand comprising a base member, a standard on said base member, a shelf member detachably and adjustably supported in connection with said standard, means for retaining said shelf member in predetermined positions of adjustment on said standard, said shelf member being composed of separate shelf parts having a common pivot on said means and arranged centrally with reference to said standard and extending at opposite sides of said standard and adjustable relatively to each other on said pivot, means involving brace levers adjustably coupled with said first named means for supporting said shelf parts in different positions of adjustment, said brace levers being adjustably coupled with said shelf parts, and said shelf member including the separate parts, said supporting means and the brace levers constituting a unit detachable with respect to the standard.
9. A display stand of the class described comprising spaced standards, a shelf member detachably and adjustably coupled with said standards, means at spaced intervals on said shelf member into and through which the standards are adapted to pass for retaining the shelf member in predetermined positions of adjustment on the standards, and said shelf member being composed of pivotally coupled parts arranged at opposite sides of the standards and adjustable relatively to each other, and the pivots of said parts being

common and arranged on said means and centrally with reference to said standards.

10. A display stand of the class described comprising spaced standards, a shelf member detachably and adjustably coupled with said standards, means at spaced intervals on said shelf member into and through which the standards are adapted to pass for retaining the shelf member in predetermined positions of adjustment on the standards, said shelf member being composed of pivotally coupled parts arranged at opposite sides of the standards and adjustable relatively to each other, the pivots of said parts being common and arranged on said means and centrally with reference to said standards, and means adjustable with reference to said first named means for retaining said parts in different positions of adjustment.

11. A display stand of the class described comprising spaced standards, a shelf member detachably and adjustably coupled with said standards, means at spaced intervals on said shelf member into and through which the standards are adapted to pass for retaining the shelf member in predetermined positions of adjustment on the standards, said shelf member being composed of pivotally coupled parts arranged at opposite sides of the standards and adjustable relatively to each other, the pivots of said parts being common and arranged on said means and centrally with reference to said standards, means adjustable with reference to said first named means for retaining said parts in different positions of adjustment, said last named means comprising oppositely disposed levers and said levers being adjustably coupled with said shelf parts, and said standards comprising tubular members with means on one end of one member for coupling the same with an adjacent member.

12. A display stand of the class described comprising spaced standards, a shelf member detachably and adjustably coupled with said standards, means at spaced intervals on said shelf member into and through which the standards are adapted to pass for retaining the shelf member in predetermined positions of adjustment on the standards, said shelf member being composed of pivotally coupled parts arranged at opposite sides of the standards and adjustable relatively to each other, the pivots of said parts being common and arranged on said means and centrally with reference to said standards, means adjustable with reference to said first named means for retaining said parts in different positions of adjustment, said last named means comprising oppositely disposed levers and said levers being adjustably coupled with said shelf parts, said standards comprising tubular members with means on one end of one member for coupling the same with an adjacent member, and another shelf member

similar to the first named shelf member and detachably and adjustably coupled with said standards and being of less dimensions than the first named member and positioned thereabove.

5 13. In a display stand of the class described a shelf unit comprising independent shelf parts, tubular shelf couplings intermediate said parts and at spaced intervals thereon for mounting said shelf parts on supports and for movably coupling said shelf parts on a pivot common to both, arranged on said couplings, and said couplings including means for retaining the shelf unit in connection with said supports.

10 14. In a display stand of the class described, a shelf unit comprising independent shelf parts, tubular shelf couplings intermediate said parts and at spaced intervals thereon for mounting said shelf parts on supports and for movably coupling said shelf parts on a pivot common to both, arranged on said couplings, said couplings including means for retaining the shelf unit in connection with said supports, and levers on said shelf parts and adjustably attached to said tubular couplings.

15 In testimony that I claim the foregoing as my invention I have signed my name this
20 23rd day of July, 1926.
